ELBERT R. CHANDLER, OF GUNTERSVILLE, ALABAMA, ASSIGNOR TO WEBSTER B. HEIDT, OF GUNTERSVILLE, ALABAMA.

WINDLASS WATER-ELEVATOR.

1,228,295.

Specification of Letters Patent.

Patented May 29, 1917.

Application filed August 9, 1916. Serial No. 114,054.

To all whom it may concern:

Be it known that I, ELBERT R. CHANDLER, a citizen of the United States, residing at Guntersville, in the county of Marshall and State of Alabama, have invented new and useful Improvements in Windlass Water-Elevators, of which the following is a specification.

The present invention relates to improvements in windlass water elevators and has for its object to provide a device of this character which shall possess the superior advantages of durability and general efficiency.

15 The invention consists in the construction, arrangement and combination of parts set forth in the following description and falling within the scope of the appended claims.

In the drawings:

20 Figure 1 is an elevation of the improvement,

Fig. 2 is an end view of the same,

Fig. 3 is a top view of the same,

25 Fig. 4 is a vertical longitudinal sectional view approximately on the line $x-x$ of Fig. 2,

Fig. 5 is a similar sectional view illustrating the arrangement of parts when the bucket has been raised to swing the water 30 chute to close the well tube and deliver the water through the spout, and

Figs. 6 to 8 are details.

Similar characters of reference designate corresponding parts throughout the several 35 views.

In the drawings, 1 designates a suitable support preferably in the nature of a platform which is arranged over and may form a closure for the open top of a well or other 40 source of water supply.

Secured to and rising vertically from the platform is a frame, the same including front and rear spaced uprights 2 and 3 respectively, the rear uprights being of a less height 45 than the front. The uprights are preferably constructed of iron, the rear members 3 being provided with angularly horizontally disposed extensions 4 connected to the front uprights 2. The front uprights have arranged therebetween and secured thereto a pipe tube 5 having an outwardly extending discharge spout 6 which preferably has its upper edges flanged to receive the closure 7

which protects the top of the spout, and formed with the spout at the lower and inner portion thereof is a substantially rectangular chamber or pocket 8 which is arranged integrally with or connected to the pipe 5. The pocket 8 projects a distance beyond the pipe proper sufficient to receive 60 therein a water chute 9. The chute comprises a flat body portion 10 which is pivotally secured, as at 11, between the sides of the pocket 8 so that the upper face of the body will be in a line with the lower wall of 65 the discharge spout when the chute is swung to an approximately horizontal position in a manner which will presently be described. The body 10 has a round rear wall which snugly engages with the pipe 5 when the 70 said chute is in the said horizontal position and both the sides and said rounded rear portion of the chute have a flange 12 of some suitable flexible material, such as rubber or thin leather. The body 10 preferably has 75 an upper facing of metal which is formed with an extension providing a lip 13.

The numeral 14 designates a latch member which is pivotally secured to the body 10 of the water chute and which is preferably in the nature of a flat strip of metal and which passes through an elongated opening 15 in the outer wall of the pocket 8. The latch bar 14 is provided with a notch 16 which is adapted to engage with 80 the lower wall provided by the opening 15 when the chute is swung to its horizontal or discharge position.

The numeral 17 designates a bail member 90 which has its opposite arms pivotally connected to the sides of the body of the chute inward of the flange 12 thereof, and the connecting member of this bail is formed with a horizontally disposed eye 18.

The windlass is indicated by the numeral 19, and journaled between the uprights 3 preferably at the juncture of their horizontal extensions 4. The shaft of the windlass is preferably bent to provide the same with a handle 20, and wound around the said 100 windlass is a cable 21 which passes over a pulley 22 arranged between the connecting member for the uprights 2 depending from and central over the open top of the pipe 5. If desired and as shown in the drawings 105 the uprights 2 adjacent the upper connect-

ing portion thereof may be curved rearwardly so that the pulley will be properly positioned with relation to the center of the pipe 5. The cable 21 passes through an elongated opening in a flange cap 23 which provides a closure for the pipe 5 and through the eye 18 of the bail 17 and is connected with a bail or handle 24 provided upon a bucket 25 that is adapted to 10 be arranged in a well or other source of supply and is adapted to be drawn through the pipe 5 by the said cable 21. The bucket has its bottom formed with a preferably centrally arranged valve seat normally closed by a gravity valve 26, the stem 27 of said valve normally extending below the bottom of the pocket.

Any number of tube members 28 may be connected to the lower end of the pipe section 5 so that the bucket will be properly guided from the supply of the well through the pipe 5. The bucket is of a length sufficient to permit of its handle portion 24 engaged with the eye 18 of the bail 17 of the 25 water chute to swing the chute upon its pivot to permit the same through the medium of its latch member 14 being retained horizontally with relation to the pipe 5 and in a discharge position with relation to the 30 discharge spout 6. After the drum has been actuated to wind the cable thereon to permit of the arrangement of parts as just stated, the handle of the cable is released, permitting the bucket to drop by gravity so 35 that its valve stem 27 will contact with the upper face of the water chute, permitting the water to flow from the said pocket, through the chute and through the discharge spout 6.

40 Suitable brace members 29 may be employed for connecting the rear uprights 3, and if necessary, spring supports may be provided for the front uprights as well as for the pipe 5.

45 The latch bar will hold the water chute in a horizontal position until actuated to permit of the same swinging into the pocket. The windlass may be provided with a suitable stop so that the pocket may be retained 50 by the cable above the chute and its valve stem out of contact with the said chute. Thus it will be noted that any desired quantity of water may be permitted to flow from the bucket through the chute and so it is

not at all necessary that all the water in the 55 bucket be dispensed therefrom at one time.

From the above description, taken in connection with the accompanying drawings, the simplicity of the device, as well as the advantages thereof will it is thought be 60 perfectly apparent to those skilled in the art to which such invention appertains without further detailed description.

Having thus described the invention, what I claim is:

1. In a device of the class described, the combination with a well, a platform of the well, a frame upon the platform, a pipe member supported by the frame, a discharge spout formed upon the pipe member, a 70 pocket formed with the spout and the pipe member disposed below the spout and outward of the pipe member, a water chute pivoted between the sides of the pocket, said chute including a body member having a 75 flexible flange adapted to contact with the pipe and with the sides of the chute when the same is in a discharge position to be wholly received in the pocket when in an inoperative position, a latch for holding the 80 chute in a discharge position, a bucket playing in the pipe, said bucket having a valved bottom provided with an extending stem, a bail for the discharge chute provided with an eye, a cable for the bucket passing 85 through the eye, and a windlass upon the frame for the cable.

2. In a device for the purpose described, a base, a frame upon the base, a pipe supported between the front uprights and the 90 frame, a windlass from the rear uprights of the frame, a cable trained over the pulley of the connecting member of the front uprights of the frame and connected with the valve in the pipe, said pipe having a discharge 95 spout, a pocket formed with the discharge spout and with the pipe, a pivoted water chute in the pocket, a notched latch rod connected with the water chute and passing through the elongated opening in the pocket, 100 a flexible flanged side for the chute, the bail having an eye through which the cable passes and which is connected with the chute, and a lipped base plate upon the body of the chute.

105 In testimony whereof I affix my signature.

ELBERT R. CHANDLER.
